RAILWAY RAIL SUPPORT

Harry Etheridge, Zelienople, Pa.

Application August 2, 1934, Serial No. 738,059

10 Claims. (Cl. 238—110)

My invention relates to that type of railway track structure wherein the support for the rails and rail joints are individual in that they do not bridge the space between the rails as is the case 5 with the conventional cross tie.

In modern practice such individual rail supports are usually formed of concrete generally reinforced with metal, and the concrete which carries the load and assumes the thrusts tends to 10 disintegrate.

Better practice is to employ a metal framework to carry the load using the concrete or other plastic material to supply the necessary floating weight and to brace or support the metallic elements and to protect the latter from atmospheric 15 deterioration.

Practical illustrations of such use of concrete or other plastic material are to be found in Letters Patent No. 2,004,369, issued to me June 20 11, 1935 and my pending patent application Serial No. 714,933, filed March 10, 1934.

In said patent application Serial No. 714,933 I disclose a rail support wherein the perimetral wall or surface which when the support is embedded in the ballast provides equal resistance in 25 all directions against movement.

The present invention comprises further improvements in rail supports provided with circular perimetral walls, and is of annular shape 30 with a center which is tamped and filled with ballast when the support is in place.

The cross sectional shape of the annular support is preferably of inverted U-shape and the trough thereof is filled with some suitable hardened plastic material, such as concrete or an asphaltum composition.

I preferably provide the trough with cross struts or webs which reinforce the opposite walls and also aid in permanently anchoring the filling 40 material in place.

The track rail is supported transversely of the support and is bolted to flanges or suitable portions of the metallic annulus. To prevent relative lateral movement between the rails and the 45 support, the base of the rail is received in sunken seats, the side walls or shoulders which define the seats being formed as opposed convex surfaces to permit the standard supports to be used on curves in either direction in addition to their use on 50 tangents.

As an additional support for the rail adjacent the center of the annulus, and especially where the supports are to be used at rail joints, I prefer to provide an upwardly bowed arch springing 55 from the interior wall of the annulus and having

a flattened crown which supports the rail or the rail joint, as the case may be, from beneath. I may also employ a flat platform supported by the arch and supporting from beneath the portion of the rail or rail ends across the metallic 5 annulus.

I prefer to form the annulus, its flanges, struts, arch and supporting plate as an integral casting which should preferably be of copper bearing malleable or cast steel. 10

I provide novel means for fastening the rails to the support.

To prevent inward tipping of the rail supports I offset them toward the center of the track.

Other novel features of construction, and also 15 of arrangement of parts will appear from the following description.

In the accompanying drawing, wherein I have illustrated a practical embodiment of the principles of my present invention, Fig. 1 is a plan 20 view of one of the individual rail supports with a rail mounted thereon.

Fig. 2 is a cross sectional view of the support taken along the line 2—2 in Fig. 1.

Fig. 3 is a view similar to Fig. 1 but showing 25 a. modification.

Fig. 4 is a cross sectional view taken along the line 4—4 in Fig. 3.

Fig. 5 is an elevation of the rail support looking 30 from the right in Fig. 3.

Fig. 6 is an enlarged detail view showing the form of fastener which I provide to secure the base of the rail to the support.

Fig. 7 is a view similar to Fig. 4 but showing 35 the intermediate supporting arch and also the intermediate rail platform.

Referring first to Figs. 1 and 2, the metallic annulus 1 is of inverted U cross sectional shape having a flat top and preferably having the opposite walls of its trough 2 connected together and reinforced by cross-struts or webs 3 positioned at intervals around the annulus. The trough 2 is cast full of material in a plastic state which hardens and forms a filling 4. Such material may be concrete or some other suitable material, such for instance, as a composition of asphaltum, sand and gravel or broken stone. 45

The rail 5 is disposed transversely of the support, as illustrated in Figs. 1 and 2 and beneath 50 the rails at either side of the support are outwardly extending brackets 6 which also support the rail from beneath. Such brackets might, if desired, extend inwardly of the annulus, instead of outwardly, but owing to convenience in apply- 55

ing the fasteners to the rails the outwardly extending bracket is preferable.

The brackets 6 are wider than the rail base, as shown in Fig. 1 and a sunken seat 7 is provided

5 extending across the top of the annulus and the bracket to receive the base of the rail, as indicated in dotted lines in Fig. 5, the seat being of such depth that the base extends upwardly out of the same.

10 The side walls 8 of said seats are convexedly arcuate, as illustrated in Fig. 1, so that the rail supports may be used with curved rails on curves in either direction.

At either side of the rail base the bracket is 15 provided with a vertical bolt hole 9 to receive bolts 10 which are used to clamp the fastener plates 11 down on the rail base, as illustrated in Fig. 6. The fasteners 11 are provided with downturned flanges 13 which fit against the sides of the 20 brackets and prevent rotation of the fastener and the engaging end of the fastener is beveled as at 14 to engage the inclined surface of the rail base. The fastener does not contact with the top of the bracket 6 except at its flanged end, so that by 25 tightening the bolt 10 the fastener is spring clamped on the rail. 15 represents a socket nut arranged to receive the bolt 10 and arranged to be held from rotation by the adjacent flat edge of the bracket 6. The bolt 10 is screwed down 30 through the fastener plate 11 and the bolt hole 9 into the nut 15 and is provided with a suitable locking device, such as indicated at 16 in Fig. 6. To prevent the rail supports from tipping inwardly under moving loads, I offset them toward 35 the center of the track as illustrated in Fig. 1. In a support of say 40 inches in diameter, the offsetting of the support toward the center of the track should be about 2.2 inches.

Referring now to Figs. 3, 4 and 5, I illustrate the 40 outer and inner annular walls of the support as corrugated which stiffens them and which also aids materially in anchoring the support in the ballast, which latter of course surrounds the support and fills the central opening or bore.

45 In Fig. 7 I show an arched truss 17 springing from the inner annular wall of the support and preferably provided with a flattened top surface to under-support the rail intermediate of its seats 7.

50 The arch is cast integrally with the body of the annulus and may be of inverted channel cross sectional shape as indicated in dotted lines in Fig. 7. Again as a further support to the rail a platform 18 may be provided bridging the center 55 of the support and under-supporting the rail, said platform being integral with the truss 17.

It will be noted that while the annulus is filled 60 with material, the load is carried by the metal from the rail to the ballast beneath the support. Again the summer heat is likewise carried directly to the ground so that the tendency of the rail to elongate and shift by warping is counteracted.

In ordinary railway construction I prefer to 65 make the supports of approximately 40 inches in diameter and space them about 10½ inches apart with about 5½ inches between the brackets of adjacent supports.

The resistance of an ordinary cross tie to side 70 movement is of course provided by the end area of the tie which is usually about 8 inches wide by 6 inches deep. In the case of my improved rail support, one hundred and eighty degrees of its outer and inner diameters are effective to resist 75 thrust in any direction. Tests have shown that

the resistance of fourteen of my supports to side thrust is approximately thirteen times that of seventeen standard cross ties per each thirty feet of track.

A track built with my supports is a substantially 5 permanent construction and requires little or no repairs and being made of copper bearing steel resists corrosion.

Again I am enabled to tamp the ballast under 10 and around the annulus from the inner and outer sides thereof which enables me to obtain a substantial rock bed for the rail support and which also increases the ballast resistance between the rails which provide an improved condition for 15 electrical track circuits.

Although I prefer to make my improved rail support in the form of a true annulus with a circular perimetral wall, such wall may be oval or of other arcuate form and the resistance of the support to movement in the ballast will be greatly 20 increased compared to that opposed to endwise movement by the conventional cross-tie. Thus as used in this specification the term annulus is not to be construed as confined to a circle but also 25 includes an oval or other inclosed form.

I claim:—

1. An individual support for a railway rail comprising a metallic annulus of inverted substantially U cross sectional shape, brackets extending 30 from the walls of said annulus at opposite locations, the transversely disposed rail being supported by the top of the annulus and said brackets, sunken seats in the top of the annulus to receive the rail bases, and fasteners engaging the brackets and clamping the rail base in said seats. 35

2. An individual support for a railway rail comprising a metallic annulus of inverted substantially U cross sectional shape, a filling of hardened plastic material for the trough of such annulus, brackets extending from the walls of said annulus 40 at opposite locations, the transversely disposed rail being supported by the top of the annulus and said brackets, sunken seats in the top of the annulus to receive the rail bases, and fasteners engaging the brackets and clamping the rail base 45 in said seats.

3. An individual support for a railway rail comprising a metallic annulus of inverted substantially U cross sectional shape, brackets extending 50 from the walls of said annulus at opposite locations, the transversely disposed rail being supported by the top of the annulus and said brackets, sunken seats in the top of the annulus to receive the rail bases, and fasteners engaging the brackets and clamping the rail base in said seats, 55 the side walls of said seats being arcuate to receive a curved rail.

4. An individual support for a railway rail comprising a metallic annulus of inverted substantially U cross sectional shape, a filling of hardened 60 plastic material for the trough of such annulus, brackets extending from the walls of said annulus at opposite locations, the transversely disposed rail being supported by the top of the annulus and said brackets, sunken seats in the top 65 of the annulus to receive the rail bases, and fasteners engaging the brackets and clamping the rail base in said seats, the side walls of said seats being arcuate to receive a curved rail.

5. An individual support for a railway rail 70 comprising a metallic annulus of an inverted substantially U cross sectional shape, the rail being disposed transversely of and fastened on the top walls of the annulus, and an arch truss sprung from the inner walls of the annulus and 75

supporting the rail intermediate of the surrounding wall of the annulus.

6. An individual support for a railway rail comprising a metallic annulus of an inverted substantially U cross sectional shape, a filling of hardened plastic material for the trough thereof, the rail being disposed transversely of and fastened on the top walls of the annulus, and an arch truss sprung from the inner walls of the annulus and supporting the rail intermediate of the surrounding wall of the annulus.

7. An individual support for a railway rail comprising a metallic annulus of an inverted substantially U cross sectional shape, the rail being disposed transversely of and fastened on the top walls of the annulus, a rail supporting platform spanning the center of the annulus and supporting the rail from below, and an arch truss sprung from the inner walls of the annulus and supporting said platform.

8. An individual support for a railway rail comprising a metallic annulus of an inverted substantially U cross sectional shape, a filling of hardened plastic material for the trough thereof, the rail being disposed transversely of and

fastened on the top walls of the annulus, a rail supporting platform spanning the center of the annulus and supporting the rail from below, and an arched truss sprung from the inner walls of the annulus and supporting said platform. 5

9. A railway rail support comprising an inclosing double wall which is continuous in a horizontal plane and has the cross sectional shape of an inverted trough and which is provided at opposite points with transversely disposed sunken 10 seats to receive the base of the rail, which seats are located in the top surface of the wall, and means to secure the rail to said support.

10. A railway rail support comprising an inclosing double wall which is continuous in a 15 horizontal plane and has the cross sectional shape of an inverted trough and which is provided at opposite points with transversely disposed sunken seats to receive the base of the rail, which seats are located in the top surface of the wall, said 20 seats being provided with curved walls to accommodate longitudinally curved rails, and means to secure the rail to said support.

HARRY ETHERIDGE. 25
